UNITED STATES PATENT OFFICE.

HORACE SHEBLE, OF PHILADELPHIA, PENNSYLVANIA, ASSIGNOR TO HAWTHORNE AND SHEBLE MANUFACTURING COMPANY, OF PHILADELPHIA, PENNSYLVANIA, A CORPORATION OF PENNSYLVANIA.

DESIGN FOR A HORN FOR TALKING-MACHINES.

No. 38,106.

Specification for Design.

Patented June 26, 1906.

Application filed January 9, 1905. Serial No. 240,361. Term of patent 7 years.

To all whom it may concern:

Be it known that I, HORACE SHEBLE, a citizen of the United States, residing in Philadelphia, Pennsylvania, have invented a certain new, original, and ornamental Design for a Horn for Talking-Machines, of which the following is a specification.

The figure shown in the accompanying drawing is a perspective view of a talking-machine horn, showing my new design.

I claim—
The ornamental design for a horn for talking-machines, as shown.

HORACE SHEBLE.
